UNITED STATES PATENT OFFICE.

CHARLES F. YARDLEY, OF HARTFORD, CONNECTICUT.

RAIL-ANTICREEPING DEVICE.

1,201,415.

Specification of Letters Patent. Patented Oct. 17, 1916.

Application filed March 6, 1916. Serial No. 82,275.

To all whom it may concern:

Be it known that I, CHARLES F. YARDLEY, a citizen of the United States, residing at Hartford, in the county of Hartford and State of Connecticut, have invented certain new and useful Improvements in Rail-Anti-creeping Devices, of which the following is a specification.

This invention relates to rail anti-creeping devices, among the many objects of the invention being the provision of an article of this character which is simple in construction, which will not damage the rail, which can be easily and quickly applied and which will effectually prevent movement of the rail in the direction of traffic. The appliance possesses other features of novelty and advantage, which with the foregoing will be stated at length in the following description, of that form of embodiment of the invention which I have selected for illustration in the drawings accompanying and forming part of the present specification. I do not restrict myself to this particular disclosure; I may depart therefrom in several respects within the scope of the invention defined by the claims following the description.

Referring to said drawings: Figure 1 is a top plan view of said device, the rail being shown in longitudinal section and a part of the tie showing in full lines, the anti-creep being in its operative position. Fig. 2 is an elevation of the device and showing in cross section the base portion of a rail, the former being shown in working relation. Fig. 3 is a view corresponding practically to Fig. 2, showing by full and dotted lines a way of applying the article. Fig. 4 is a developed view of a blank from which that form of appliance herein shown can be made.

Like characters refer to like parts throughout the several figures.

In Fig. 2 I have shown the base portion of a rail 2. The rails may be connected to the ties in any of the ways now in use, and the ties may be in turn laid in any desirable manner, these being points with which the invention is not concerned.

Preferably though not necessarily the anti-creep is made in one piece, and although any suitable material may be utilized for this purpose, what is known as "high tension" or "spring steel" answers satisfactorily in this connection, the thickness of the

stock depending upon the size of the rail in conjunction with which the anti-creep is to be used.

The device includes in its construction the body portion 4, the upper flat edge 5 of which is adapted under operative conditions to bear substantially and solidly against the under surface of the base of the rail as shown in Fig. 2. Rising from the bearing surface 5 at the ends thereof are the faces 6 and 7 practically perpendicular or at right angles to the edge 5. The distance between these gripping or clamping faces 6 and 7 is practically equal to the width of the base of the rail. This distance between the faces 6 and 7 may be a little greater or a little less than the width of the base of the rail, but I prefer that it be a trifle less for a reason that will hereinafter appear. It will be understood that the faces 6 and 7 present the inner parts of jaw portions 8 and 9 situated in the present case at the terminals of the body portion 4, these jaw portions as will be understood, jointly clamping or gripping the rail base onto which they are driven. The anti-creep also comprises an abutment or stop portion as 10 separated or spaced from the body portion 4 but considerably shorter as shown, than the latter. This abutment portion 10 may be parallel with said body portion, being adapted to engage against the side face of the tie adjacent said body portion or nearest the line of traffic which line is indicated by the arrow in Fig. 1. The abutment portion 10 is joined to the connecting or body member 4 or to the jaw member 8 thereof in some suitable way as by the bowed connecting part 11 which as represented is curved outward from the rail. The abutment portion 10 is also shown provided with a rail engaging face 12. This rail-engaging face as illustrated is in the plane of the edge 5. It need not necessarily be co-extensive with the abutment portion, however, being located practically at the free end thereof, the upper portion of said abutment portion back of the rail engaging face 12 being cut away or removed as at 13 for clearance. The jaw portion 8 is provided with an inward projection or lug 14 in alignment perpendicularly with or in the vertical plane of the body 4, this projection 14 being adapted to overhang one lateral portion of the rail base. While the projection 14 is connected with the jaw portion 8, the jaw

portion 9 has associated with it the resilient tongue 15 spaced from the body 4 and connected with the said jaw portion 9 or with the body 4 of which said jaw portion forms 5 a terminal by the laterally bowed connecting part or neck 16. Initially the under surface of the tip of this resilient tongue 15 is practically under the base of the rail 2 at the side thereof opposite the jaw 8 as will 10 hereinafter appear.

In applying the anti-creeper the following procedure may be adopted: Initially the abutment 10 will be placed against the proper surface of the tie 3 and what is 15 shown as the left side of the base of the rail 2 will be entered in the recess or notch formed jointly by the edge 5, face 6 and overhanging projection 14, the device being at this time at a downward inward slant 20 (Fig. 3) from the recess and the tongue 15 being under the base of the rail. With the aid of a suitable implement the body 4 is elevated until the side edges of the rail base are received between the faces 6 and 7; the 25 motion continuing until the edge 5 nearly strikes the under surface of the rail at which point the faces 6 and 7 will tightly and firmly grip the rail. As a matter of fact the body or connecting member 4 is connected with the rail practically by a driving fit, so that when said connecting member is 30 positioned on the rail, it becomes virtually a rigid or solid part thereof and the purchase of the jaws 8 and 9 on the rail is so 35 tight and firm as to effectually resist with the aid of the abutment member 10 ordinary endwise thrusts. At this point the body portion is almost horizontal, the abutment portion 10 bearing against the tie as it 40 should in practice. The tongue 15, however, is still below the rail base. With the aid of a suitable implement and through a fulcrum afforded if necessary by the tie, the tongue is elevated and as soon as its under flat edge 45 is flush with the upper surface of the rail base, the tongue automatically or by its own resiliency instantly springs across said base. If necessary the edge 5 is brought by the aid of a suitable tool against the under surface 50 of the rail. It will be noted that the free portion of the tongue is curved outward, so that as the tongue is elevated in the manner described, this curved portion by engaging the inner edge of the rail base 55 is cammed outward until at such time as the tongue reaches its high position as already set forth. When the tongue is positioned over the rail the creeper in its entirety is prevented from dropping, although the grip 60 of the faces 6 and 7 upon the rail is sufficient under normal or usual conditions to preclude such a possibility. There may be cases where the side edges of the rail may flake and in such an event the faces 6 and 7 65 cannot obtain their maximum hold, but

owing to the fact that the lug 14 and tongue 15 overlie the rail, it is not possible for the anti-creeper to drop from place. The tongue is both perpendicularly and laterally yieldable, which is a feature of advantage for the 70 reasons already set forth. It is not directly connected to the body but is united thereto by the connecting portion or neck 16, said tongue as a consequence being positively spaced or separated from the body. In view 75 of this circumstance the body can be applied initially to the rail in the position which it is to ultimately occupy and which is practically at right angles to the rail, which is a 80 feature of some importance.

The line of thrust is indicated by the arrow in Fig. 1, as I have already set forth, and when such thrust is applied to the rail it is directly transferred to the body portion 4 and through the bowed portion 11 to 85 the abutment portion 10. The anchored tie 3 prevents movement of the anti-creeper and the latter in turn movement of the rail in the direction indicated. As the device is of 90 resiliient character, it is clear that if any abnormal thrust be applied to the rail, the pull of the rail owing to the fact that the abutment 95 10 is fixed, will cause the tongue 15 to swing toward the body 4 and will thus cause a progressive increase in pressure of the 100 tongue on the rail proportionate to the increase in thrust applied to the rail. The result of this is that when said tongue is thus acted upon it is drawn onto and up the base of the rail and into biting engagement 105 therewith, the bite being along the inner edge thereof. In view of this circumstance it follows that the body 4 is both advanced on an arc struck from an axis vertically intersecting the resilient portion 11 and is also 110 tipped, so that if possible to cause the faces 6 and 7 to more closely embrace the rail. This latter condition will always ensue should there be any looseness in fit of the faces 6 and 7 on the rail caused for instance 115 by scaling of the rail.

In Fig. 4 I show a suitable blank from which the anti-creeper hereinbefore described can advantageously be made. While it is desirable that the appliance be made in 115 a single piece, this may not always be necessary. When, however, it is thus made the blank in question is one of several that are quite suitable for the purpose. In describing this blank I will as near as possible use 120 the reference symbols hereinbefore employed. This blank can be cut from sheet metal by the aid of suitable dies or otherwise and it comprises the body portion 4, the upper edge of which is straight. From 125 this upper edge 5 the straight faces 6 and 7 rise, the face 6 being overhung by the lug 14. From what is shown as the left end of the body there is the downwardly deflected portion 11 terminating in a straight part 10. 130

The blank is bent on itself at the left end so as to produce the resilient bowed connecting portion 11 to which I have already referred. At the right end of the blank there is a prolongation 23 which is doubled on itself to produce the overhanging tongue 15 already described.

In addition to the points of advantage I have already alluded to, I might refer 10 among others to the following: Frozen ballast will not loosen the anti-creeper, nor will reverse traffic affect it. No special tools are required to mount or dismount the device, a small hammer and bar being all that is 15 necessary to obtain these functions. It tightens automatically at a large number of points, six in the present case. It is self-maintaining and self-adjustable.

In actual use two of the anti-creepers 20 should be placed at the center of each rail opposite the joint in the opposite rail; there may be conditions where more may be required.

I have spoken of the yieldability vertically and laterally of the tongue 15. The 25 vertical yieldability is due to the resilience of the body portion 4, while the lateral yieldability is due to the resilient connection of said tongue with said body portion.

30 It will be noticed that the tongue 15 is connected with the body portion 5 resiliently at a point outwardly beyond adjacent jaw 9. This condition is obtained in the construction shown, by providing the body portion 35 4 at a point outwardly beyond said jaw 9 with a return bend, the free part of which presents the tongue 15, to which I have already alluded, while the part 16 constitutes the bent portion of the return bend. 40 Owing to this construction, it will be clear that the base or butt of the tongue 15, is not connected directly with the body portion, but is connected with it through the resilient neck part 16, in view of which I can connect the device with the rail in the manner 45 set forth.

What I claim is:

1. An anti-creeper comprising a body portion having jaws to engage the base of 50 a rail, one end of the body portion being provided with a tie engaging abutment yieldingly connected with said body portion and the other end thereof being provided with a tongue also yieldingly connected 55 with said body portion, the tongue being adapted to engage over the upper side of the base.

2. An anti-creeper comprising a body portion having jaws to engage the base of a 60 rail, the jaws being separated a distance agreeing practically with the width of said base whereby the body portion can be driven onto the base from the underside of the rail when approximately at right angles thereto, 65 one end of the body portion being provided

with a tie-engaging abutment yieldingly connected with said body portion and the other end thereof being provided with a tongue, also yieldingly connected with the body portion, the tongue being adapted to engage over the upper side of the base. 70

3. An anti-creeper comprising a body portion having jaws to engage the base of a rail, the jaws being separated a distance 75 agreeing practically with the width of said base whereby the body portion can be driven onto said base from the underside of the rail when approximately at right angles thereto, a tie-engaging abutment, a resilient portion connecting the tie-engaging abutment with one end of the body portion and a tongue connected resiliently with the other end of the body portion, the whole being 80 made in one piece.

4. An anti-creeper comprising a body 85 portion having jaws to engage the base of a rail and a return bend at one end of the body portion, the free portion of the return bend constituting a tongue to engage over the base of the rail. 90

5. An anti-creeper comprising a body portion having jaws to engage the base of a rail, one end of the body portion having a tongue to engage over said base and resiliently connected with said body portion at 95 a point outwardly beyond the adjacent jaw.

6. An anti-creeper comprising a body provided with jaws at its ends, the upper edge of the body being straight and the operative portions of the jaws extending up 100 from said straight portion at approximately right angles thereto, a tie-engaging abutment, a resilient portion connecting the tie-engaging abutment with the body, a tongue to engage over the base of the rail, a resilient portion connecting the tongue with the body at one end thereof, the opposite end of the body having a lug to coöperate with the adjacent jaw and to overhang the rail base. 105

7. An anti-creeper comprising a body, the upper edge of which is straight, jaws at the ends of the body, the operative faces of the jaws extending upwardly from said straight edge at approximately a right angle thereto, 115 a tie-engaging abutment, the upper portion of which is in the plane of said edge, a resilient portion connecting said abutment with said body at one end of the latter, a tongue to overlie the base of the rail, a resilient portion connecting the tongue with the adjacent end of the body, and a lug extending inwardly from the first mentioned jaw and adapted to overlie the base of the rail approximately opposite said tongue. 120

8. An anti-creeper comprising a body portion having jaws to engage the base of a rail, the jaws being separated a distance 125 agreeing practically with the width of said base, said body portion having at one end

thereof a return bend, the free part of which constitutes a tongue to engage over the upper side of said base.

9. An anti-creeper comprising a body portion having jaws to engage the base of a rail, the jaws being separated a distance agreeing practically with the width of said base, said body portion having a tie-engaging abutment resiliently connected therewith at one end, and a tongue resiliently connected with the opposite end of said body portion.

10. An anti-creeper comprising a body portion having jaws to engage the base of a rail, the jaws being separated a distance agreeing practically with the width of said base, the body portion having a return bend at one end, the free portion of which constitutes a tongue to overlie said base and having at the opposite end a tie-engaging abutment resiliently connected therewith, said body portion further having a lug to engage over the base of the rail opposite that part thereof engaged by the tongue, the whole being made in one piece.

11. An anti-creeper comprising a body portion provided with jaws to engage the base of a rail and also provided with a return bend at one end thereof, the free portion of which constitutes a tongue to overlie said base, said body portion further having a tie-engaging abutment.

12. An anti-creeper comprising a body portion provided with jaws to engage the base of a rail and also provided at one end thereof with a tongue to overlie said base, said tongue being yieldingly connected with

the body portion at a point outwardly beyond the adjacent jaw.

13. An anti-creeper comprising a body portion having jaws to receive the base of a rail, said body portion having a tongue to engage over said base and yieldably connected with said body portion at a point outwardly beyond the adjacent jaw, the tongue extending inward into the space bounded by the planes of the operative portions of the jaws.

14. An anti-creeper comprising a body portion having jaws to receive a rail, said body portion having a return bend connected therewith at a point outwardly beyond the adjacent jaw, the free portion of the return bend being extended inward into the space bounded by the planes of the operative portions of the jaws to thus engage over the base of the rail.

15. An anti-creeper comprising a body portion having jaws to grip a rail from the underside thereof, said body having a tongue resiliently connected therewith and to engage under the base of the rail when said base is initially positioned between the jaws, said tongue being outwardly movable by the rail on the upward movement of the body portion and being adapted to snap over the upper side of the base of the rail when in line therewith.

In testimony whereof I affix my signature in presence of two witnesses:

CHARLES F. YARDLEY.

Witnesses:
